(57) **CLAIM**

The ornamental design for a folding pedal powered tricycle, as shown and described.

DESCRIPTION

FIG. 1 is a front axonometric view of a folding pedal powered tricycle in accordance with our present invention; FIG. 2 is a front axonometric view of the tricycle in a folded position;

FIG. 3 is a rear axonometric view of the tricycle in an opened position;

FIG. 4 is a rear axonometric view of the tricycle in a folded position;

FIG. 5 is a left side elevational view of the tricycle in an opened position;

FIG. 6 is a left side elevational view of the tricycle in a folded position;

FIG. 7 is a front elevational view of the tricycle in an opened position; and,

FIG. 8 is a top plan view of the tricycle in an opened position.
